UNITED STATES PATENT OFFICE.

FIRMAN R. CRIST, OF SCRANTON, PENNSYLVANIA.

VACUUM COVER.

1,411,323.

Specification of Letters Patent.

Patented Apr. 4, 1922.

Application filed October 25, 1921. Serial No. 510,204.

To all whom it may concern:

Be it known that FIRMAN R. CRIST, a citizen of the United States, residing at Scranton, in the county of Lackawanna and State 5 of Pennsylvania, has invented certain new and useful Improvements in Vacuum Covers, of which the following is a specification.

This invention relates to vacuum covers or closures for receptacles and the primary 10 object of the invention is to provide an improved, hermetically sealing device for maintaining a practically constant temperature within a container for a long duration of time.

One of the objects of the invention is to 15 provide a non-porous vacuum cover or closure adapted to fit within the neck portion of a container or receptacle and held in locking engagement therewith, whereby a constant temperature may be maintained by 20 preventing heat or cold passing through the walls.

A still further object of the invention is 25 the provision of a glass or metallic vacuum sanitary closure adapted for sealing various types of vacuum containers or receptacles and particularly vacuum cans or vacuum bottles, including means for gripping said closure in locking engagement with the neck 30 of the container or receptacle, whereby an effective seal is had preventing the passage of heat or cold so that a constant temperature may be maintained within the receptacle.

Another and very important object of the 35 invention is the provision of a sanitary closure of the type above set forth, adapted for use on practically any type of metallic or non-metallic receptacle, and one in which 40 the parts are extremely simple in construction, easily assembled, rigid and durable, highly efficient in operation, practical and capable of being manufactured at a very low cost, whereby its commercial possibilities are 45 greatly enhanced.

The invention will be best understood 50 from a consideration of the following detailed description taken in connection with the accompanying drawing forming a part 55 of this specification, with the understanding, however, that the invention is not confined to any strict conformity with the showing in the drawing, but may be changed and mod-

ified so long as such changes and modifications mark no material departure from the 55 salient features of the invention as expressed in the appended claims.

I attain the above objects and others by the accompanying drawings, wherein:

Figure 1 is a vertical sectional view taken 60 through a conventional form of a vacuum container and illustrating the application of the novel cover constructed in accordance with the invention.

Figure 2 is a transverse sectional view 65 through the cover and neck of the container, with the closure removed.

Figure 3 is a detail view, showing the slot arrangement and the neck of the container.

Figure 4 is a further detail view showing 70 the lug or pin on the cover adapted to cooperate with the respective slots in the neck of the container.

Figure 5 is a plan of the closure member; 75 and

Figure 6 is a cross sectional view through the same.

Referring now to the drawings, wherein like parts designate corresponding parts throughout the several views, 5 designates 80 generally, the body of a vacuum receptacle or retainer, such as a vacuum bottle or milk can, and 6 the inner face or wall thereof, separated by suitable lugs 7, whereby a vacuum space is formed between said walls 85 and adapted to have the air exhausted therefrom through the sealing off tube 9 in the bottom thereof, as clearly shown by Figure 1 of the drawings.

The restricted or neck portion 10 of the 90 said container has its walls flared outwardly to receive my novel and improved, non-porous, glass or metallic closure member, designated in its entirety by numeral 11, which is shaped to conform to the neck 95 portion of the receptacle. The said closure member 11 is also provided with a vacuum space 12, about the side walls and bottom thereof, and a sealing off tube 13, whereby the air may be exhausted from the said air 100 space to thus provide a vacuum closure member, whereby the heat may be retained within the receptacle for a long duration of time.

Referring now particularly to Figure 1, it 105 will be observed that the closure member 11

is formed with a flange 14, overlying the top edge of the double walled receptacle, said flange extending only to the outer wall 15 thereof, so as to confine a gasket 16, thus producing a positive sealing means between the said closure member and the receptacle proper. The top of the closure member 11 is formed with a depression 17, and a web 18, constituting a handle, whereby the said closure member may be properly seated within the neck of the bottle, as clearly understood.

The cover 19, for said receptacle, is also provided with the flaring walls 20, said walls having the usual protuberance or projection 15 21 thereon for engagement with the L-shaped slots 22, oppositely disposed on the neck of the receptacle, so that when the cover is seated thereon and turned the said protuberances 21 will lie in engagement 20 with the slots 22 and positively lock the same thereon. It will also be observed that the side wall 20 of the cover is bent inwardly as shown at 24, in such manner as to overlie the top or flanged portion 14 of 25 the closure member, so that upon rotation of the said cover the closure member will be pressed firmly into engagement with the gasket in making an air tight seal between the receptacle and said closure member.

30 In the accompanying drawings, I have illustrated my invention embodied in one form by way of example, and which in practice has been found to be highly satisfactory in obtaining the desired results. It 35 will be obvious however, that other embodiments may be adapted, and that various changes in the details of construction may be resorted to by those skilled in the art without departing from the spirit and scope 40 of the invention. It is furthermore understood that the invention is not necessarily limited or restricted to the precise elements shown except in so far as such limitations are specified in the subject matter being 45 claimed.

Having thus described and illustrated my invention, what I claim as new and desire

to secure by Letters Patent of the United States is:

1. In a device of the class described the 50 combination with a container having spaced walls, of a non-porous closure adapted to fit within the neck portion of said container and provided with a vacuum space adjacent the outer wall and bottom thereof, a flange formed with said closure extending to the outer wall of the neck portion thereof and a cover for said container cooperating with the flange of the closure to produce an air-tight seal.

2. In a device of the class described, the combination with a container having spaced walls, of a non-porous closure adapted to fit within the neck of said container and provided with a vacuum space adjacent the 65 outer and bottom wall thereof, a flange formed with the top of said closure extending to the edge of the outer wall of the neck portion and a cover for said container having an inwardly bent bead on its side wall 70 adapted to bear on the flange of the closure to effect an air tight seal.

3. In a device of the class described, the combination with a container having spaced walls, of a non-porous closure adapted to fit within the neck of said container and provided with a vacuum space adjacent the outer wall and bottom thereof, a flange formed on the outer edge of said closure, a countersunk hand hold in the top thereof, a cover 80 for said container overlying its neck portion, a lug and slot connection between the cover and the neck portion for locking the same and an inwardly bent bead formed on the side wall of the cover bearing against the 85 flanged closure as the cover is moved into locking engagement with the neck of the container.

In testimony whereof I affix my signature in presence of two witnesses.

FIRMAN R. CRIST.
